UNITED STATES PATENT OFFICE.

HARRY T. GOSS, OF RUTHERFORD, NEW JERSEY, ASSIGNOR TO BUNDY
MANUFACTURING COMPANY, A CORPORATION OF NEW YORK.

PRINTING-MACHINE.

No. 881,058.

Specification of Letters Patent.

Patented Sept. 13, 1906.

Application filed July 13, 1905. Serial No. 289,509.

To all whom it may concern:

Be it known that I, HARRY T. Goss, a citizen of the United States, and a resident of Rutherford, in the county of Bergen and State of New Jersey, have invented certain new and useful Improvements in Printing-Machines, of which the following is a specification.

My invention relates to printing-machines. It is especially useful in that class of machine in which printing-type are stationary at the time of the printing and the hammers are movable to give a printing-blow, and especially in machines in which sheets of paper as distinguished from narrow strips are used and in which the sheet of paper is movable relatively to the type and printing-hammers, so as to bring any part of the sheet upon the printing-line between the hammers and the type.

It is also especially useful in machines in which characters are brought upon a printing-line representing a single operation, and where a second set of type are provided for representing and printing the total of a number of operations.

My invention has for one of its objects to so arrange the type and hammers and paper-carrying mechanism that printing can be effected upon any part of the sheet without interfering with the means for operating either the printing-hammers or the type.

It has also for its object to improve the paper-feed mechanism in such machine and generally to simplify and improve machines of the character shown and described herein.

In the drawings accompanying this application and forming part thereof, I have shown a printing and adding machine provided with two sets of type, one representing the characters set up at each operation of the machine and the other set adding from the first set and representing the total, and in which the printing-hammers are arranged in a carriage on top of the machine, but are operated from the main body of the machine. While my invention is particularly useful in connection with such kind of machines, it is not limited to use with such machines, but may be used with any printing or adding machines adapted thereto.

Referring now to the preferred form of my device shown in the drawings accompanying this specification, Figure 1 is a plan view of

the complete machine. Fig. 2 is a central longitudinal section. Fig. 3 is a detail of the outside view of the carriage. Fig. 4 is a vertical section of the carriage and certain of the connecting parts taken on the lines 4-4 of Fig. 1. Fig. 5 is a central longitudinal section of the carriage. Fig. 6 is a detail showing a rear view of the paper-feed mechanism. Fig. 7 is a rear view of the hammers and crossover-rods. Fig. 8 is a side view of the same taken in the direction of the arrow at 65 the left of Fig. 7. Fig. 9 is a side view taken in the direction of the arrow at the right of Fig. 7. Fig. 10 is a front view of the carriage. Fig. 11 is a portion of a printed strip. Fig. 12 is a detail of the carriage-lock. 70

My improvement is shown in connection with a printing and adding machine. The details of this machine are of no importance so far as my present invention is concerned, as any printing or adding machine may be used in connection with it for which it is adapted. My improvement is especially adapted for use with a printing or adding machine in which the type are stationary at the time when the printing-blow is given as 80 distinguished from that class of printing and adding machines in which type are moved to deliver the printing-blow. In Figs. 1 and 2 I have shown in general outline in connection with my improved carriage a machine of the former type. All the details of this machine are not given, the machine being represented sufficiently to give a general idea of how my improved carriage is combined with such a machine. In the machine shown 11 are the 90 keys, which are arranged, as usual, in a bank provided with series, each series being of the same denominative value. These keys are operated by being depressed in the usual way and are locked in down position and the unoperated keys in up position by any suitable device. These locking devices are not shown in detail. The keys are returned to normal position when released by means of springs 2. The operation of a key throws down the lower 100 part of its shank 3 into the path of a dog 4. The keys of the series are arranged at different points along this path, so that the movement of the dog is differentiated for different keys, dependent upon their value. The operation of the keys is merely to set a stop in the path of the dog 4, and this stop unlocks the dog from a motor device and holds the 105

dog at the set position. The movement of the dog and its connecting parts operate segments 5, carrying type 6. Any suitable device may be employed for operating the main parts of the machine. As shown, they are operated by a handle 7. The operation of this handle gives a continuous rotary movement to shaft 8 by one complete revolution of the shaft for each operation of the handle. Fast on this shaft is a lever 9, which has a shoulder 10 engaging with a finger 11 of dog 4. Dog 4 is pivotally mounted at 12 on a rock-lever 13, loosely mounted on shaft 8. The dog is normally held with its nose in the position shown in Fig. 2 by spring 14. When handle 7 is operated, shoulder 10 of lever 9 forces dog 4 to rotate to the right, as viewed in Fig. 2, until the nose of dog 4 strikes the shank of a depressed key, or if no key has been depressed, strikes a zero-stop 15, which normally projects into the path of dog 4, but which is removed from the path whenever a key of a series is operated. The devices for this purpose are of no importance so far as my present invention is concerned, and will not be further described. Rock-lever 13 is connected by a link 16 with an arm 17 of segment 5. When dog 4 strikes the zero-stop or the shank of a key, it is rotated on its pivot, throwing finger 11 out of engagement with shoulder 10. These parts are so arranged that when this happens lever 9, fast on shaft 8, can continue its rotary movement, leaving dog 4 and its connecting rock-lever 13 in the set position to which they have been moved. They are held in this position by an arm 18, having a turned portion 19 adapted to take into notches 20 in a locking part 21. The segments 5 are thus held in the position to which they have been moved, bringing upon the printing-line underneath a hammer 22 the type representing the value of the key depressed, or if no key has been depressed, the zero-type.

It will of course be understood that there is a segment 5, dog 4, and connecting parts for each series of the bank of keys.

The segments 5 are loosely mounted upon a shaft 23, which is carried by two supporting-arms 24, one at each side of the machine, the latter being mounted upon a rock-shaft 25. This rock-shaft carries an arm 26, provided with a roller 27, engaging with a cam 28 on cam-shaft 29. The cam-shaft 29 is driven in unison with shaft 8 by any suitable means. These means are not shown, as they form no part of the invention. The mounting of shaft 23 on supporting-arms 24 with the cam arrangement causes segments 5 to be thrown at the commencement of the movement of handle 7 slightly to the right and downward to engage with the teeth of gear-wheel 31. The movement of dog 4 to the right causes segments 5 to rotate to the left, as viewed in Fig. 2, as already described, and

this movement gives a proportionate rotation to gear-wheels 31. The latter mesh with gears 32 of adding-wheels 33.

Any suitable carrying-mechanism may be provided. A carrying mechanism, shown in general outline but not in full detail, consists of a set of gear-wheels 34, provided with a series of pins 35. When each wheel has moved its full complement, one of these pins strikes the nose of a rock-lever 36, pivoted at 37, and held by a spring 38, in the position shown in Fig. 2. 39 is a locking-lever for holding it in its set position. The details of this forming no part of the invention will not be further described. Mounted on the lower part of rock-lever 36 is a pawl 40 for engaging the lip 41 of a carrying-rack 42, which is provided with teeth at its upper end, as shown. This carrying-rack is mounted so as to have a slight vertical movement on arm 43 fast on shaft 44. In the operation of the machine by handle 7 this shaft is slightly rotated after the adding operation to throw the teeth of carrying-rack 42 into engagement with the teeth of gear 34, this taking place after the adding operation is completed, or, in other words, after segments 5 have separated from gears 31. Pawl 40 has a turned projection 45, which normally lies to one side of the path of rotation of pins 46, mounted spirally on shaft 47. These spiral pins are rotated by means of a handle 7 through devices not shown. When a pin 35 strikes rock-shaft 36, it moves turned portions 45 into the path of one of the pins 46. When these pins are moved, the corresponding pin 46 will strike this turned part 45 and rock pawl 40. When this rocking takes place, the nose of pawl 40 is immediately over lip 41, and will force carrying-rack 42 downward, so as to move gear 34 one point. It will, of course, be understood that pawl 40 engages with lip 41 of the carrying-rack of the next higher order. This is not shown in detail, as it forms no part of the invention.

Any suitable means may be employed for resetting the various devices in their column positions. I have shown a handle 48, (see Fig. 1,) for this purpose. All of the resetting mechanism connected with it is not shown. I have merely indicated on Fig. 2 an arm 49, carrying a resetting arm 50, having a nose 51, adapted to be moved up into the path of rotation of pins 52 on gear 31, and to move along that path and strike one of these pins and move gears 31 back to zero position, this movement, of course, moving the adding-wheels 33 to zero position also. Resetting-arm 51 is normally out of the path of pins 52, but is raised into the path by means of a cam-slot 53, through which extends a supporting-bar 54, which runs across the machine.

The segments 5 are held in a set or printing position by means of locking-pawls 56, mounted on a shaft 57. These pawls are nor-

5 mally held out of engagement by means of a projection 53 on a rock-shaft 59, but by any suitable device the rock-shaft is moved so as to release pawls 56, which are then thrown down into locking position by springs 60. The hammers 23 and their connecting parts are mounted in a movable carriage 61. This carriage is mounted at the top of the machine and is free to move backward and forward along slide-rods 32. The carriage has a casting 63 at each side, each casting provided at each end with a bearing 64, encircling slide-rods 32. These castings are part of and support the carriage. These two castings are secured together by tie-rods 65 66. The entire carriage is pivoted on the rear tie-rod 65, and can be raised up, as shown in dotted lines in Fig. 5. The carriage is tilted up for the purpose of enabling the operator to examine the printed matter. Mounted upon the rear tie-rod 65 is a casting 66, which runs across the machine, making it pivotally connected to the casting 63 on each side of the machine. This casting 66, in connection with a cover-plate 67 and two side plates 68 69, forms a housing for the hammers and the paper feed, the hammers projecting forward through an opening 69 in the casting 66. The opening 69 is large enough to permit the hammers to swing vertically to deliver their printing-blow.

35 A carriage for supporting the paper-rolls and paper-receptacle and their connections is provided, mounted upon the main carriage 61 and so arranged as to have a lateral movement on that carriage. The framework of this paper-carriage consists of a substantially rectangular casting 70, having at its rear two supporting-rods 71 free to slide 40 through bearings 72, which bearings are a portion of the casting 66. These bearings 72 consist of two upper ones and two lower ones and are arranged, preferably, near the center of the machine. The lateral paper-carriage 45 is thus free to have an extended lateral movement in either direction sufficient to bring any part of the sheet of paper carried by the paper-rolls beneath the hammers. By means of this arrangement any part of a wide sheet 50 can be printed upon. A column of figures may be printed and added at the left of the sheet of paper and then the paper can be moved so as to print a second column, and then a third, and so on. 73 is a paper-55 roll of the ordinary construction, and 74 is a pressure-roll. The paper, which preferably is a wide sheet—as, for example, a wide letter-head or similar paper—is put behind the guard-plate 75, between the rollers 73 and 60 74, and then turned down under the hammers. The carriage is then raised and the end of the strip is pushed into a throat or opening 76 of a paper-receptacle 77. This receptacle is preferably shown as being substantially circular in cross-section. As the

paper is fed into the receptacle, it curls up and is stored there in the manner shown in Fig. 6.

70 The means shown for feeding a sheet of paper are as follows, (see particularly Figs. 3; 70 4, and 6.) The paper is introduced into the paper-receptacle 77 in the manner indicated, thumb-wheels 78, fast on the shaft of paper-roll 72, assisting in this operation. The sheet is pushed in between the rolls until the 75 point of the sheet where you wish to begin the printing is under the printing mechanism. Each operation of the machine thereafter feeds the paper sheet outward a certain distance. This distance can be regulated, as 80 will be presently described. 79 is a bar projecting up through the casing of the machine. It is adapted to be operated by the driving mechanism of the machine, so as to be raised and retracted at each operation of the machine. The means for doing this are not shown and will not be described. When this bar 79 is raised, it strikes upon roller 80, secured to lever 81, pivoted at 82, and carrying a link 83, pivoted to a rock-lever 84 and pivoted and splined in the upper supporting-rod 71. 85 The splining is done by means of pin 85 in rock-lever 84 and groove 86 in supporting-rod 71. Spring 87 holds these parts in their normal or down position, as shown in Fig. 6. 90 Fast on the outer end of supporting-rod 71 is a lever 88, pivoted at its lower end to a link 89 and connected at its other end to a pawl-connecting plate 90 loosely mounted on the shaft of roll 73. On this pawl-supporting plate is 100 mounted a spring-actuated pawl 91 and adapted to engage with a ratchet 92 fast on the shaft of roll 73. This pawl is normally held out of engagement with the ratchet by means of a pin 93, projecting sidewise from it and 105 resting normally upon a feed-adjusting plate 94 loosely mounted on the shaft of roll 73 and locked in any set position by means of a spring-pressed pin 95, working in a socket 96 by means of the casting 70. Pin 95 takes 110 into any one of a number of notches 97 in the plate 94. The plate 94 can be adjusted to any desired position by taking hold of a knob 98, pulling the pin outward, and moving plate 94 by means of a handle 99. As shown, 115 pawl 91 has a movement which is adapted to feed ratchet 92 eight teeth, if plate 94 is in its lowermost position. By moving that plate upward to any point the amount of feed can be limited, as desired. A wheel 100, mounted 120 at the front of the paper-supporting carriage and adapted to roll along the front tie-rod 65, supports the paper-supporting rod at its forward end and at the same time permits it a free lateral movement. By means 125 of this the position of the roll 73 can be accurately adjusted with regard to the top of the machine. Just in front of wheel 100 is a pointer 101, coacting with a scale 102 on front tie-rod 65. This enables the paper-130

supporting carriage to be accurately adjusted laterally, enabling the operator to print a column upon the print of paper at any predetermined point. Immediately the rear of 5 wheel 100 is in positive lock 103 for the purpose of preventing jar to the paper-supporting carriage.

At the front of the carriage on each side is an ear 104, secured to casting 63 to aid in 10 shoving the whole carriage to the rear to print a total. The hammers 22 can be operated by any suitable operating means connected with the operating-handle of the machine. As shown, these devices are as follows: The hammers are loosely mounted on 15 a shaft, each hammer having a crossover-rod 106 of well-known construction connecting it to a toe 107, which projects downward over an opening 108 in the upper part of the 20 casing of the main machine.

109 represents trips for rocking the toe-levers and through them for raising the hammers. After a hammer has been raised and 25 trip 109 slips by toe 107 the hammer is retracted by means of a spring 110 and caused to deliver a printing-blow. The upper arm 111, connected with each of the toes 107, except the outer-one, is curved, as shown in Fig. 4, so as to clear the other crossover-rods. 30 112 112 are rebound-springs of ordinary construction for the hammers.

At each operation of the machine by handle 7 the toes 109 are moved forward or to the left, as shown in Fig. 4. These trips are 35 mounted on a sliding support 113. These supports are free to move longitudinally on a rocking lever 114, pivoted at 115. Normally rocking levers 114 are in the position shown in Fig. 4, with supports 113 in their 40 downward position, so that trips 109 are not high enough to engage toes 107. The operation of a machine of any series rocks rocking lever 114, so as to raise the right-hand end and bring trip 109 high enough to engage its 45 toe 107. The means for doing this form no part of the present invention and will not be further described. If no key in a series is depressed, trip 109, corresponding to it, remains in its downward position, and while it 50 is moved forward it does not engage its toe 107 and the hammer is not operated.

When the carriage is in the forward position, the numbers set up by the keys are printed upon the sheet of paper successively. 55 If it is desired to print a total at any time, the operator seizes his ears 104 and pushes the entire carriage as far back as it will go. As the carriage goes backward the roll 80 rides up on cam 116, giving to the paper-feed 60 mechanism exactly the same feeding movement as when rod 79 pushes that roller upward. This causes the paper to be fed one point, leaving a space between the press composing a column of figures and the total. 65 The hammers are operated to print the total

by means of a second and similar set of trips 117. There is of course one of these trips for each hammer. These trips, like trips 109, are normally in down position, where they will not engage toes 107, but are set up into 70 operative position by the adding-wheels. In the first movement from zero of any adding-wheel setting up its corresponding toe the toes remain in set position until the entire adding mechanism is reset. Any suitable 75 means may be provided for setting the toes 117 in set position or in resetting them. As shown, these trips are pivotally mounted on a rocking lever 118, pivoted at 119, and are operated by means of crossovers 120 and 80 connecting-links 121, connecting to levers 122, which are operated by pins 52 of gear 31. All of these crossovers and their connecting parts are frictionally held.

If it is desired, my improved carriage and 85 connecting parts may be used with a strip of paper instead of removable sheets. For this purpose I have shown a wheel 123, supported in brackets 124 in the rear of the machine, the paper being threaded through a guiding-slot 125, mounted on the housing 67 on the carriage 61. This construction has the advantage that the strip of paper when not used can always be left threaded in the machine and when in use can be cared for under 95 the paper-supporting carriage and between the feed-rolls.

By means of my improvement printing-machines can be used in which the type are stationary at the time of the delivery of the 100 printing-blow and the printing is accomplished by the movement of the hammers, and yet a relatively wide sheet of paper may be used movable laterally and longitudinally of the type and printing-hammers, so that 105 any part of the paper can be brought on the printing-line between the type and the printing-hammer. By my improvement also printing from two sets of type at any part of such a sheet of paper can be effected. Also 110 the printing can be done either upon such a loose wide sheet which can be manually fed into or out of the machine, or the printing can be done upon a narrow strip of paper without unnecessary trouble in adjusting the 115 strip at each operation. By means of my improved device all interference between the sheet in its movements with or from the operating mechanism operating either the hammers or the type is dispensed with. This is a 120 great advantage, because in machines of the character above described it has heretofore been impossible to use other than a narrow strip of paper because of such interference. By means of my improved paper-receptacle 125 constructed and arranged and combined as shown this advantage is obtained.

Many modifications in and many departures from the particular form of devices shown in the drawings and specifically de- 130

scribed in the specification can of course be made without departing from my invention, the essentials of which are set forth in the claims appended hereto.

5. What I claim as new, and desire to secure by Letters Patent, is—

1. The combination of type-bearing mechanism, printing-hammers, operating means for one of these parts projecting into the 10 plane of the paper on the printing-line, means for moving the paper relative to the type-bearing mechanism and the printing-hammers, and a paper-receptacle for storing in a small compass that part of the paper in the 15 machine which is not on the printing-line, whereby interference between the paper and the said operating means will be prevented.

2. The combination of type-bearing mechanism, printing-hammers, means for operating the printing-hammers projecting into the plane of the paper on the printing-line, means for moving the paper relative to the type-bearing mechanism and the printing-hammers, and a paper-receptacle for storing in a 25 small compass that part of the paper in the machine which is not on the printing-line, whereby interference between the paper and the said operating means will be prevented.

3. The combination of type-bearing mechanism, printing-hammers, operating means for one of these parts projecting into the plane of the paper on the printing-line, a carriage adapted to support the paper and to move it relatively to the type-bearing mechanism and the printing-hammers, a paper-receptacle for storing in a small compass that part of the paper in the machine which is not on the printing-line, whereby interference between the paper and the said operating means will 35 be prevented.

4. The combination of type-bearing mechanism, printing-hammers, means for operating the printing-hammers projecting into the plane of the paper on the printing-line, a carriage adapted to support the paper and to move it relatively to the type-bearing mechanism and the printing-hammers, a paper-receptacle for storing in a small compass that part of the paper in the machine which is not 45 on the printing-line mounted on the carriage and movable therewith, the hammers and paper-receptacle being so constructed and arranged relatively to each other that the movement of neither is interfered with by the other.

5. The combination of type-bearing mechanism, printing-hammers, means for operating the printing-hammers projecting into the plane of the paper on the printing-line, a carriage adapted to support the paper and to move it relatively to the type-bearing mechanism and the printing-hammers, a paper-receptacle for storing in a small compass that part of the paper in the machine which is not 60 on the printing-line mounted on the carriage

and movable therewith, the hammer-arms being shaped so as to pass around the paper-receptacle so that neither the movement of the carriage nor that of the printing-hammer is interfered with.

70

6. The combination of type-bearing mechanism, printing-hammers, operating means for one of these parts projecting into the plane of the paper on the printing-line, a carriage adapted to support the paper and to move it relatively to the type-bearing mechanism and the printing-hammers, a paper-receptacle having a portion of a curved shape in cross-section, the hammer-arms being curved to pass around such curved portion of the 75 paper-receptacle, the paper-receptacle being mounted on the carriage and moving therewith.

80

7. The combination of type-bearing mechanism, printing-hammers, operating means for one of these parts projecting into the plane of the paper on the printing-line, a carriage adapted to support the paper and to move it relatively to the type-bearing mechanism and the printing-hammers, a hollow 85 paper-receptacle provided with curved interior walls adapted to wind up the paper in the machine which is not upon the printing-line, and curved printing-arms for the printing-hammers embracing the curved walls of 90 the paper-receptacle whereby interference between the paper and the said operating means will be prevented.

95

8. In a printing-machine the combination of type-bearing devices arranged in the body 100 of the machine and adapted to be stationary during the printing operation, differential means for bringing upon the printing-line the different characters upon such devices, printing-hammers arranged on top of the machine, 105 operating means for operating these hammers projecting into the plane of the paper on the printing-line, a carriage adapted to support the paper and to move it relatively to the type-bearing devices and the printing-hammers, a paper-receptacle mounted on 110 said carriage and movable therewith, and having a portion of its interior walls of curved shape in cross-section, and hammer-arms curved in shape to pass around such curved 115 walls of the paper-receptacle, whereby interference between the paper and the hammer-operating means will be prevented.

115

9. The combination of type-bearing mechanism, printing-hammers, operating means for one of said parts projecting into the plane 120 of the paper on the printing-line, a carriage adapted to support the paper and its feeding mechanism and to move them relatively to the type-bearing mechanism and printing-hammers, paper-feeding mechanism mounted on the carriage and movable therewith, a paper-receptacle also mounted on the carriage and movable therewith and adapted to store in a small compass that part of the pa- 130

per in the machine not on the printing-line, the hammers and paper-receptacle being so constructed and arranged relatively to each other that the movement of neither is interfered with by the other.

10. The combination of type-bearing mechanism, printing-hammers, operating means for one of said parts projecting into the plane of the paper on the printing-line, a carriage adapted to support the paper and its feeding mechanism and to move them relatively to the type-bearing mechanism and printing-hammers, paper-feeding mechanism, including means for automatically feeding the paper adapted to be actuated by the printing mechanism, and means for feeding the paper adapted to be manually operated, such means being mounted upon and movable with the carriage, a paper-receptacle 15 also mounted on the carriage and movable therewith and adapted to store in a small compass that part of the paper in the machine not on the printing-line, the hammers and paper-receptacle being so constructed 20 and arranged relatively to each other that the movement of neither is interfered with by the other.

11. In a printing-machine the combination of two sets of stationary type arranged 30 in the body of the machine one set for printing totals, both type adapted to be stationary during the printing operation, differential means for bringing upon the printing-line of one of the sets of type different characters upon the 35 devices of such set, means for adding from such set to the total set, a set of hammers arranged upon the top of the machine, means for operating the hammers arranged in the body of the machine and projecting into and 40 through the plane of the paper on the printing-line, a main carriage upon which the printing-hammers are mounted movable so as to bring the printing-hammers into printing alinement with either set of type, a secondary carriage adapted to carry the paper 45 and mounted on the main carriage and movable thereon at right angles to the line of movement of said main carriage, a paper-receptacle for storing in a small compass that 50 part of the paper in the machine not on the printing-line mounted on the secondary carriage and movable therewith, whereby the characters on the printing-line of either set of type may be printed upon any part of the 55 paper and whereby interference between the paper and the hammer-operating means will be prevented.

12. The combination of type-bearing mechanism, printing-hammers, means for operating the printing-hammers projecting into the plane of the paper on the printing-line, a carriage adapted for supporting and moving the paper relative to the type and the printing-hammers, paper-feeding means 65 mounted on and movable with the carriage,

a paper-receptacle also mounted on and movable with said carriage for storing in a small compass that part of the paper in the machine not on the printing-line, whereby the paper may be printed upon at any part of its surface and whereby interference between the paper and the said operated means will be prevented. 70

13. The combination of type-bearing mechanism, printing-hammers, means for 75 operating the printing-hammers projecting into the plane of the paper on the printing-line, a carriage adapted for supporting and moving the paper relative to the type and the printing-hammers, paper-feed means adapted to be manually operated mounted upon and movable with said carriage, a paper-receptacle also mounted on and movable with said carriage for storing in a small compass 80 that part of the paper in the machine not on the printing-line, whereby the paper may be printed upon at any part of its surface and whereby interference between the paper and the said operated means will be prevented. 85

14. The combination of type-bearing 90 mechanism, printing-hammers, means for operating said hammers projecting into the plane of the paper on the printing-line, a carriage adapted to carry the paper and to move it relatively to the type and printing-hammers, paper-feed means for automatically feeding the paper on each printing operation, printing means adapted to be manually operated mounted upon and movable with the carriage, a paper-receptacle mounted upon 95 and movable with the carriage having curved interior walls adapted to wind up that part of the paper in the machine not on the printing-line and curved printing-arms encircling the curved walls of the paper-receptacle, 100 whereby interference between the paper and the operated means will be prevented. 105

15. The combination of type-bearing mechanism, printing-hammers, means for operating the printing-hammers projecting into the plane of the paper on a printing-line, a carriage adapted to carry the paper and move it relatively to the type and printing-hammers, means for automatically feeding the printing-paper at each printing operation, means for feeding the paper adapted to be manually operated mounted upon and movable with the carriage, a paper-receptacle for storing in a small compass that part 110 of the paper in the machine not upon the printing-line, whereby the paper may be moved to effect the printing at any point upon its surface and may be inserted and withdrawn at pleasure and whereby interference between the paper and the operated 115 means will be prevented. 120

16. The combination of type-bearing mechanism, printing-hammers, means for operating the hammers projecting into the plane of the paper on the printing-line, a car- 130

riage adapted to carry the paper and to move it laterally across the type and printing-hammers and so constructed and supported as to laterally overrun such type and printing-hammers so as to bring any part of the width of the paper upon the printing-line opposite the hammers and type, a paper-receptacle also mounted upon and movable with the carriage for storing in a small compass that part of the paper in the machine not upon the printing-line, whereby printing can be effected upon any part of the width of the paper and whereby any interference between the paper and said operated means will be prevented.

17. The combination in a printing-ma-

chine of a paper-feed roll adapted for use either with a loose sheet of paper or a permanent recording-strip, a roll adapted to hold such permanent recording-strip and a guiding-chute leading from said roll toward the paper-roll, all so constructed and arranged that the recording-strip may be left in position in the chute when the machine is used for printing upon a loose sheet of paper. 20 25

In testimony whereof I have signed my name to this specification in the presence of two subscribing witnesses.

HARRY T. GOSS.
